ATTORNEY

UNITED STATES PATENT OFFICE.

WILLIAM O. CAMPBELL, OF AETNA, INDIANA.

BOAT-HULL.

1,295,117.

Specification of Letters Patent. Patented Feb. 25, 1919.

Application filed June 27, 1917, Serial No. 177,315. Renewed July 19, 1918. Serial No. 245,770.

To all whom it may concern:

Be it known that I, WILLIAM O. CAMPBELL, a citizen of the United States, and resident of the city of Aetna, in the county 5 of Lake and State of Indiana, have invented certain new and useful Improvements in Boat-Hulls, of which the following is a specification containing a full, clear, and exact description, reference being had to the 10 accompanying drawings, forming a part hereof.

My invention relates to improvements in boat hulls wherein the siding consists of open-work metallic sheathing secured to the 15 framing and to which a filler or body is applied in a plastic condition and which when "set" is impermeable to water.

My object is to provide a boat hull of inexpensive and durable construction whose 20 siding is readily obtainable and more readily and quickly applied to the frames or skeletons of boats than the materials now employed and which siding is of relatively light weight, possessive of relatively high 25 resistance to penetration, possessive of good resistance to the deteriorating action of the elements and which may be easily and quickly repaired.

My invention consists in the arrangement, 30 construction and combination of elements as will be fully, clearly and concisely set forth, pointed out in my claims and illustrated in the accompanying drawing, in which,

35 Figure 1 is a transverse sectional elevation of a boat hull embodying my improvements.

Fig. 2 is a fragmental elevation of the hull, and

40 Fig. 3 is an enlarged fragmental, sectional detail view, showing one form of means for securing the metallic sheathing to the hull frame and the relation of the filler to the sheathing.

45 Referring to the drawings, by numerals, 5 designates the keel of the hull or vessel, preferably consisting of a metallic beam of T-shape, sectionally and extended as a single piece, or rigidly connected sections 50 throughout the length of the hull, or from stem to stern and to which the lower ends of the ribs 6 are secured, and which ribs extend in opposite directions transversely of the hull and from the keel, as single 55 pieces, or rigidly connected sections of angle irons to the rails 7 of the hull, and which

"rail" ends of the ribs are connected by stanchions 8, preferably of metal.

To this frame I secure one or more plies of openwork metallic sheathing 9, by means 60 of rivets 10, the plies being held relatively spaced by washers or spacers 11.

In my drawings, see Fig. 1, I show such plies of metallic sheathing as being continuous from rail to rail of the hull, which 65 is my preferred construction and while I have not illustrated the same I prefer that such plies are also preferably continuous from stem to stern.

Obviously, in relatively large hulls, it 70 would be difficult to make one section or piece of sheathing cover the entire hull, in which case I connect sections of sheathing in a manner to produce the effect of a continuous, one piece sheathing, by which expedient I may in some cases, dispense entirely with stringers between ribs, as is common.

To this sheathing I apply a filler or body 12, comprising pulp or fiber and a binder 80 which forms a plastic mass which may be readily forced through the interstices of the sheathing and adhere thereto to form therewith a reinforced body, and in a manner to completely embed both the sheathing and 85 its means of attachment or securement to the hull frame.

In order to render the mass compact and intimately contact with the sheathing, the filler may be tamped during its application. 90

The filler or body 12 may consist of easily obtainable and inexpensive material, such as sawdust, wood-pulp, wood-fiber, vegetable-fibers of various varieties, as well as various mineral and animal fibers, and the binder 95 may be any waterproof tenacious substance, such as white lead or litharge mixed with oil, or waterproof glue.

Having thus described my invention what I claim as new therein and desire to secure 100 by Letters Patent, is—

1. A boat hull comprising side rails, stanchions secured to said side rails, a keel formed of a metallic bar T-shaped in cross section, ribs secured to the keel and side 105 rails, a series of layers of open metallic sheathing secured to the ribs, the said sheathing being spaced apart, and a body of fibrous material and tenacious water-proof material pressed between the metallic sheath- 110 ing and entirely covering same.

2. A boat hull comprising a metallic keel,

- side rails and stanchions connecting the side rails, ribs secured to the side rails and keel, a plurality of open mesh, layers of metallic sheathing spaced apart secured to said ribs, 5 and a plastic wood fiber pulp mixed with a water-proof material pressed between the layers of metallic sheathing.
3. A boat hull comprising a metallic keel, side rails and stanchions, ribs connected to 10 the side rails and keel, a series of layers of open metallic sheathing spaced apart secured

to the ribs, and a plastic body consisting of wood pulp and white lead pressed between the sheathing and covering the outside sheathing.

15

In testimony whereof, I have signed my name to this specification, in presence of two subscribing witnesses.

WILLIAM O. CAMPBELL.

Witnesses:

CLARA L. PRATT,
P. I. WEGENER.
